UNITED STATES PATENT OFFICE

ROSCOE A. COFFMAN, OF HOLLYWOOD, CALIFORNIA

ENGINE

Application filed June 15, 1928. Serial No. 285,713.

The present invention has for one of its objects, the provision of an engine which will be light and compact, the structure being adapted for use primarily but not exclusively in an airplane. Another object of the invention is to provide novel means for compressing the charge. A further object of the invention is to provide novel means for introducing the fuel into the engine and for 10 scouring out the exhaust charges.

It is within the province of the disclosure to improve generally and to enhance the utility of devices of that type to which the invention appertains.

15 With the above and other objects in view, which will appear as the description proceeds, the invention resides in the combination and arrangement of parts and in the details of construction hereinafter described 20 and claimed, it being understood that changes in the precise embodiment of the invention herein disclosed, may be made within the scope of what is claimed, without departing from the spirit of the invention.

25 In the accompanying drawings:—

Figure 1 shows in longitudinal section, a device constructed in accordance with the invention;

30 Figure 2 is a sectional view illustrating the parts as they will appear at the time the charge is compressed;

Figure 3 is a longitudinal section;

35 Figure 4 is a transverse section on the line 4—4 of Figure 2, the line 2—2 of Figure 4 indicating the cutting plane for Figure 2;

Figure 5 is a section on the line 5—5 of Figure 2, the line 3—3 in Figure 5 indicating the cutting plane for Figure 3.

40 The invention includes a cylinder, embodying an outer member 1 carrying a head 2, the head and the outer member 1 being provided with the usual cooling fins 3, although the engine may be cooled in any desired way.

45 A spark plug mounting 4 is located in the head 2 and is to be taken as typical of any suitable means whereby the charge may be exploded.

50 The cylinder includes an inner member 5 extended within the outer member 1, the outer member 1 and the inner member 5 hav-

ing cooperating flanges 15 which are secured together, there being a space 6 between the outer member 1 and the inner member 5, the inner member 5 extending for a considerable distance within the outer member 1, as Figure 55 clearly shows. The space between the inner member 5 and the outer member 1 is marked by the numeral 6.

A sleeve piston 7 is mounted to reciprocate in the outer member 1 and slides in the space 6 which exists between the outer member 1 and the inner member 5 of the engine cylinder. The sleeve piston 7 has an end wall 8 which is inclined, as shown in Figures 1 and 2. The end wall 8 has an inwardly extended hub 9. In the end of the piston 7, about the hub 9 there is an annular chamber 10. Reinforcing flanges 11 extend between the body portion of the piston 7 and the hub 9, the flanges being joined to the end wall 8 of the piston. The numeral 12 marks a hollow piston rod which is mounted to slide in a gland 14 carried by the end of the inner member 5 of the piston. One end 16 of the hollow rod 12 is secured in the hub 9 of the piston 7, the space between the ends 16 of the rod 12 and the outer surface of the end wall 8 of the piston being filled by a suitable closure 75 plug 17, of any desired sort.

The end of the hollow rod 12 is closed by 80 a plug 18, which may be threaded in place, as shown in Figure 1 of the drawings. The rod 12 has an annular flange 19 which abuts against the inner end of the hub 9, and securing devices 20 connect the flange 19 with 85 the hub. The securing devices 20 may be countersunk into the hub, as shown in Figure 1 of the drawings, and the openings in the hub 9 for the devices 20 may be closed 90 as shown at 21, so that the wall 8 of the piston 7 presents a smooth surface to the firing chamber.

The numeral 22 designates a tubular guide mounted to reciprocate inside of the inner 95 member 5 of the cylinder. The guide 22 is provided with an overhanging rim 23 at one end. The guide 22 has oppositely disposed inwardly projecting bearings 24 for the reception of a hollow wrist pin 25 in 100

the ends of which headed closures 26 are mounted.

The numeral 27 denotes an inverted U-shaped yoke, the depending arms of which are mounted to swing upon the wrist pin 25 at the inner ends of the sockets 24. The lower end of the hollow piston rod 12 is threaded as shown at 28, or secured otherwise, in the intermediate portion of the yoke 27. Oil ducts 29 extend through the intermediate portion of the yoke 27.

The guide 22 is supplied in its side wall with inclined slits 30, and there are openings 31 in the guide, the openings 31 being located on the opposite side of the sockets 24 from the slits 30. The inner member 5 of the cylinder is supplied with any desired number of perforations 32 communicating with the space 6 which exists between the inner member 5 and the outer member 1 of the cylinder. Owing to the presence of the openings 32, 31 and 30, an even distribution of oil is obtained, and the piston 7 will be thoroughly lubricated as it reciprocates in the space shown at 6. There will also be adequate lubrication for the yoke 27 where it is mounted on the wrist pin 25. The numeral 33 denotes a connecting rod provided at its upper end with the bushed eye 34 mounted on a hollow wrist pin 25 between the side arms of the yoke 27. The eye 34 of the connecting rod 33, and the enclosed bushing 35, are provided with registering openings 36 which admit oil upon the wrist pin 25, within the bushing 35. The outer member 1 of the cylinder has an intake port 37 through which the fuel is forced by any suitable means (not shown). The piston 7 is provided in its side wall with an intake port 38 which is adapted to register with the intake port 37 of the outer member 1 of the cylinder. The outer member 1 of the cylinder is provided with an exhaust port 39. There is a bypass 40 in the outer member 1 of the cylinder.

The piston 7 is provided in its side wall with a port 41 adapted to register with the bypass 40. In the working end of the piston there is a channel 42, one end of which extends lengthwise of the piston, and the other end of which extends transversely of the piston and is adapted to communicate with the bypass 40.

Although the cylinder of the engine may stand in any desired position with respect to the vertical, it will be supposed that the cylinder is standing vertically, and the terms "up" and "down" will be used, for convenience, in describing how the piston 7 moves.

The piston 7 moves up to the position shown in Figure 3, until the intake port 38 of the piston 7 is in registration with the intake port 37 of the outer member 1 of the cylinder, as shown in Figures 3 and 5. The gaseous fuel is forced through the registering

ports 37 and 38, into the space between the top of the inner member 5 of the cylinder and the end wall 8 of the piston 7. The piston 7 moves downwardly, making a power stroke under the impulse of the gas which is exploded in the head 2 of the cylinder above the piston 7. As the piston 7 moves downwardly, the gas is compressed between the end wall 8 of the cylinder and the upper end of the inner member 5 of the cylinder until the piston has arrived in the position shown in Figure 2 of the drawings. As the piston 7 moves to the position shown in Figure 2 of the drawings, the port 41 in the side wall of the piston 7 comes into registration with the lower part of the bypass 40 in the outer member 1 of the cylinder and the compressed gas in the annular chamber 10 flows through the port 41 into the bypass 40.

The compressed gas moves upwardly from the bypass 40 through the passage 42 in the piston 7 and is projected upwardly with great force into the upper part of the cylinder, the exhaust being forced downwardly and laterally and outwardly through the exhaust port 39, the exhaust port being open at this time because the end wall 8 of the piston is in the position shown in Figure 2. The lateral inclination of the end wall 8 aids in the expelling of the exhaust through the port 39. The upper end of the cylinder now is full of fresh fuel and as the piston 7 moves upwardly, the charge is compressed between the end wall 8 of the piston and the head 2, the charge being exploded by any suitable means mounted in the opening 4 of Figure 1.

As the piston 7 reciprocates, the rod 12 slides in the gland 14 and motion is imparted to the guide 22, the guide reciprocating in the inner member 5 of the cylinder, below the upper end of the inner member 5, motion being transmitted to the connecting rod 33 by way of the wrist pin 25.

The inner end of the member 5 of the cylinder prevents the oil from coming into contact with the inner surface of the end wall 8 of the piston 7 and "frying out" thereon, to the detriment of the oil. Although the end wall 8 of the piston 7 is not cooled by contact with the oil, the flanges 11 will serve to cool the end of the piston. When the piston moves to the position shown in Figure 2, the compressed charge within the chamber 10 flows out from among the flanges 11, and the flanges, in this way, act as cooling vanes.

Attention is directed at this place to the overhanging rim 23 at the inner end of the guide 22. No matter how the cylinder may stand with respect to the vertical, the rim 23 serves to receive and turn back toward the opposite end of the guide, oil that may find its way into the guide.

Having thus described the invention, what is claimed is:—

1. An engine comprising a cylinder includ-

- ing an inner member and an outer member, a cup shaped sleeve piston mounted to slide between the inner and outer members of the cylinder, a guide slidable in the inner member of the cylinder, a connecting rod assembled with the guide, a rod slidable in the end of the inner member of the cylinder and connected to the piston and to the guide, means for admitting a charge within the piston for compression and means for transferring the charge from the piston to the outer member of the cylinder to effect an expulsion of the exhaust, the piston being in close, slidable contact with the inner and outer members of the cylinder, thereby to confine the compression between the end of the inner member of the cylinder and the end of the piston. 5
2. An engine comprising a cylinder including an inner member and an outer member, a cup shaped sleeve piston mounted to slide between the inner and outer members of the cylinder, means for admitting a charge into the piston for compression, means for transferring the compressed charge from the piston to the outer member of the cylinder to effect an expulsion of the exhaust, the piston being in close, slidable contact with the inner and outer members of the cylinder, thereby to confine the compression between the end of the inner member of the cylinder and the end of the piston, the guide having perforations which admit oil on the inner surface of the inner member of the cylinder whilst the guide is sliding thereon, the inner member of the cylinder having perforations which admit oil to the space between the inner and outer members of the cylinder, for the lubrication of the piston, the perforations of the guide and of the inner member of the piston cooperating to secure an even distribution of oil to the piston. 10
3. An engine comprising a cylinder including an inner member and an outer member, a cup shaped sleeve piston mounted to slide between the inner and outer members of the cylinder, an annular guide slidable in the inner member of the cylinder and provided at its inner end with an overhanging oil-deflecting rim, a connecting rod assembled with the guide, a rod slidable in the inner member of the cylinder and connected to the piston and to the guide, means for admitting a charge within the piston for compression, and means for transferring the charge from the piston to the outer member of the cylinder to effect an expulsion of the exhaust. 15
4. An engine comprising a cylinder including an inner member and an outer member, a cup shaped sleeve piston mounted to slide between the inner and outer members of the cylinder, the piston having an end wall, and the inner member of the cylinder having an end wall which prevents oil within the inner member from reaching the end wall of the 20
- piston, the end wall of the piston having internal cooling fins, a rod slidable in the inner member of the cylinder and connected to the piston, means for admitting a charge within the piston for compression, and means for transferring the charge from the piston to the outer member of the cylinder to effect an expulsion of the exhaust. 25
5. An engine comprising a cylinder having opposed heads, the walls of the cylinder being provided with an exhaust port, an inlet port, and with a passage affording a by-pass connection adjacent one end of the cylinder, and a sleeve piston reciprocable in the cylinder and having its sleeve portion slidable on and surrounding one of said heads, said sleeve portion being provided with an inlet port adapted to register with the inlet port of the cylinder, and a discharge port adapted to register with the passage of the cylinder. 30
6. In apparatus of the class described, a cylinder, a head for said cylinder having a gland extending outwardly, a piston in the cylinder, a piston rod extending through the gland, and a cylindrical bearing shoe secured to the piston rod beyond the gland, a portion of the shoe overlying the gland when the piston is at its innermost position. 35
7. In apparatus of the class described, a cylinder, a cylindrical bearing extension carried by the cylinder, a sleeve bearing slidably in the bearing extension, a piston rod secured to the sleeve bearing, and a piston connected to the piston rod reciprocable in the cylinder, the sleeve bearing being slotted to afford lubrication slots extending at an angle to the direction of movement of the sleeve bearing. 40
8. An engine comprising spaced inner and outer cylinders, a sleeve slidable in between the cylinders, and a lubricating member reciprocable within the inner cylinder, the inner cylinder having perforations cooperating with slots in the lubricating member. 45
9. An engine comprising spaced inner and outer cylinders, a sleeve piston reciprocable in the outer cylinder and having its sleeve portion slidable in the space between the cylinders, a piston rod having a bearing member engaging the inner walls of the inner piston, the inner cylinder having openings cooperating with lubricating slots in said bearing member. 50
